UNITED STATES PATENT OFFICE.

EDWARD BRUNHOFF, OF CINCINNATI, OHIO.

DESIGN FOR A CHANGE-TRAY.

44,466.

Specification for Design.

Patented Aug. 12, 1913.

Application filed March 8, 1913. Serial No. 753,100. Term of patent 7 years.

To all whom it may concern:

Be it known that I, EDWARD BRUNHOFF, a citizen of the United States, residing at Cincinnati, in the county of Hamilton and State of Ohio, have invented a new, original, and ornamental Design for Change-Trays, of which the following is a specification, reference being had to the accompanying drawings, forming a part thereof.

My new and original design comprises as illustrated a hollow body of transparent material as for instance molded glass, exteriorly of triangular outline with blunt meeting edges and slightly sloping sides, a plane horizontal upper face with a shallow concavity meeting the three faces of the triangular sides with comparatively sharp edges, and a bead around the base.

Figure 1 of the drawings is a perspective view, and Fig. 2 is a central vertical section on line *v v* of Fig. 1.

Colors are to be applied to the inner face of the body to present a particularly bright and pleasing effect. When colors are applied the appearance is that of a solid body.

I claim:

The ornamental design for a change tray as shown and described.

In testimony whereof, I have affixed my signature in the presence of two witnesses.

EDWARD BRUNHOFF.

Witnesses:

C. W. MILES,
H. THORNTON BOGERT.
